Anthony J. Lima ATTORNEY

UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

FASTENING DEVICE FOR CHASERS FOR DIE-HEADS.

1,323,584.

Specification of Letters Patent.

Patented Dec. 2, 1919.

Application filed February 12, 1919. Serial No. 276,472.

To all whom it may concern:

Be it known that I, JAMES A. EDEN, Jr., a citizen of the United States, residing in Springfield, Massachusetts, have invented 5 certain new and useful Improvements in Fastening Devices for Chasers for Die-Heads, of which the following is a specification.

My invention aims to provide an improved fastening device particularly adapted 10 for fastening chasers in carriers which are mounted in die-heads of the class shown, for example, in my application for patent Serial No. 271,631. The present fastening 15 device is simple in design and, with the carrier and chaser, can be cheaply made and will hold the chaser firmly.

The accompanying drawings illustrate 20 embodiments of the invention.

Figure 1 is a plan of a chaser-carrier of the type illustrated in my application above referred to with a chaser fastened therein according to my present improvement;

Fig. 2 is a cross-section of the same on the 25 line 2—2 of Fig. 1;

Figs. 3, 4 and 5 are similar views of other embodiments of the invention;

Fig. 6 is a plan of the carrier and devices of Fig. 5;

Fig. 7 is an enlarged detail.

Referring to the embodiments of the invention illustrated the carrier A is formed at one side with an ear in which is an opening B intended to fit over a trunnion so that

35 the carrier can be rocked to bring the point of the chaser into or out of engagement with the work, and on the opposite side has a pair of alined ears with an opening C to receive the end of a toggle by which the afore- 40 said adjustment of the carrier is effected.

Extending lengthwise between these two opposite parts is a groove D in which lies the chaser E, the groove being slightly wider than the chaser to permit the latter to be 45 moved freely therein when it is not clamped.

In Fig. 1 I have shown a chaser of a design known in the trade, having a longitudinal shoulder F along its back face which is undercut, and which has been used with a 50 correspondingly shaped fastening device to hold the chaser pressed against the back of its groove as well as down against the bottom thereof. According to my present invention this undercut shoulder is unneces-

sary, but I have shown it here to indicate 55 that the invention may be used with this design of chaser as well as with other designs. The carrier is formed with a groove G which in its lower corner is shaped similarly to the shoulder F of the chaser. A holding down 60 block H is mounted in the groove G and overhangs the shoulder of the chaser and is held down by screws J. Generally with chasers of the design shown in Fig. 2 the block H will have its corners shaped to fit 65 the shoulder F of the chaser. But with the present invention the plain block shown may be used or we may hold the chaser in place without the aid of any such holding down 70 block.

I depend primarily, and may in fact depend solely, for holding the chaser in position on a block K having teeth on its forward face engaging the teeth of the chaser and means for forcing said block against the 75 chaser so as to press the latter against the back of its groove and also down to the bottom of its groove and thus to prevent its working loose in practice. Various devices may be used for forcing the block K against 80 the chaser and for holding it in the fastening position. In the several figures of the drawing I have shown different devices for this purpose located in the portion of the carrier which is adjacent to the toothed side 85 of the chaser, all of them being easily accessible from the exposed face or side of the carrier.

According to Figs. 1 and 2 the block K is 90 of rectangular shape, located in a similar recess L in the carrier, and a screw M passes through from the side of the carrier and has its inner end bearing against the block K so as to clamp the latter and the chaser in position.

According to Fig. 3 the block K' has an inclined rear face which is engaged by the lower inclined end of a plug N lying in a vertical recess, which in turn is engaged by a screw O passing through the top of the 100 carrier. The forcing in of the screw O will press the plug N down and press the block K' inward so as to force the chaser against the back of its groove. The chaser is shown in this case with a square shoulder F' for 105 engagement by a holding down block H but this, as we have said in connection with Fig. 2, is not essential.

According to Fig. 4 the toothed block K^2 is upwardly inclined from its toothed face, lies in a corresponding recess in the carrier A and is engaged at its rear end by a screw 5 P passing also in an inclined direction downward from the top of the carrier. In the constructions of the previous figures the clamping blocks K and K' depend on their beveled engagement with the teeth of the 10 chaser to force the latter down against the bottom of its groove. In the design of Fig. 4 the clamping block K^2 is itself pressed downward as well as inward by its screw P.

In this case (as in Fig. 5) the chaser E is 15 shown without a shoulder on its back face and without any holding down device except the toothed block at the front.

According to Fig. 5 the toothed block K^3 is wedge-shaped in plan (see Fig. 6), its 20 tapered back bearing against a correspondingly tapered face of a groove in the carrier. The fastening block is driven in until it holds the chaser E firmly. In this position it is preferably clamped fast by a screw 25 Q passing down through the top face of the carrier and having its head arranged to bear on the top face of the clamping block K^3 sufficiently to prevent by friction the 30 displacement of the latter. The action of the head of the screw Q on the clamping block K^3 is to press the latter down and to 35 press the chaser against the bottom of its groove D while the wedging action of the block K^3 itself serves to press the chaser against the back of its groove, and through 40 the inclined faces of the toothed engagement, to press it against the bottom of its groove.

As its end wears or is ground off it is 45 adjusted by a screw R threaded in the carrier and bearing against a shoulder formed on the lower corner of the chaser. The chaser has teeth or serrations along its entire 50 length and is thus adapted in all positions of lengthwise adjustment for engagement 55 with the longitudinally fixed clamping block. Fig. 7 shows the relative location and design of the block and chaser so that the lower faces of the teeth S of the block bear with a camming action on the upper 60 faces of the teeth T of the chaser to force the latter down against the bottom of its groove as well as transversely against the back of such groove.

Though I have described with great particularity of detail certain embodiments of my invention yet it is not to be understood therefrom that the invention is restricted to the particular embodiments illustrated. 65 Various modifications thereof in detail and in the arrangement and combination of the parts may be made by those skilled in the art without departure from the invention as defined in the following claims.

What I claim is—

1. A chaser-carrier having a groove in combination with a chaser longitudinally adjustable in said groove, a block engaging the face of said chaser and means for pressing said block in a transverse direction 70 against the face of the chaser to press the latter against the back of its groove.

2. A chaser-carrier having a groove to receive the chaser in combination with a block having teeth adapted to engage teeth 75 on the chaser, means for pressing said block in a transverse direction against the chaser to press the latter against the back of its groove.

3. A chaser-carrier having a groove to 80 receive the chaser in combination with a block having teeth adapted to engage teeth on the chaser, means for pressing said block in a transverse direction against the chaser to press the latter against the back of its 85 groove, said block and chaser being arranged with the lower faces of the teeth of the block bearing with a camming action on the upper faces of the teeth of the chaser to force the latter down as well as press it 90 transversely.

4. A chaser-carrier having a groove in combination with a chaser adjustable longitudinally in said groove and having teeth along the entire length of its face and a longitudinally stationary block having teeth 95 engaging the teeth of the chaser and pressing the latter in a transverse direction against the back of its groove.

5. A chaser-carrier for die-heads shaped 100 for attachment at opposite sides with parts of the die-head and having a groove extending longitudinally between such points of attachment to receive the chaser in combination with a block having teeth adapted to 105 engage teeth on the chaser and means located in the portion of the carrier adjacent to the toothed side of the chaser for forcing said block against the chaser to press the latter against the back of its groove.

6. A chaser-carrier for die-heads shaped for attachment at opposite sides with parts of the die-head and having a groove extending longitudinally between such points of attachment to receive the chaser in combination with a block having teeth adapted to 115 engage teeth on the chaser and means located in the portion of the carrier adjacent to the toothed side of the chaser for forcing said block against the chaser to press the latter against the back of its groove and a screw for holding said block pressed against the chaser so as to hold the chaser pressed against the back of its groove.

In witness whereof, I have hereunto 120 signed my name.

JAMES A. EDEN, JR.
